UNITED STATES PATENT OFFICE

JAMES COOKE, OF OMAHA, NEBRASKA

FASTENER FOR DISPLAY CHARACTERS

Application filed May 5, 1930. Serial No. 449,964.

My invention relates to display characters, such as letters, figures, etc. of such form as to be adapted to be permanently secured to a wood base or mounting. The construction here disclosed is an improvement on that disclosed in my prior Patent No. 1,511,028 of October 7, 1924.

An important object of my invention is to provide efficient attaching means so arranged that no tacks or other fastening devices are visible on the exterior surface of the display character; nor is it necessary to interrupt or mar the exposed face of the character with any openings. The desired result is secured by providing bent-back portions of the body of the character and securing the attaching means in said bent back portions. The specific form of the attaching elements may be varied within the limits indicated in the claims.

A further object of my invention is to provide a fastening device that will securely hold the desired characters on either soft or hard wood supports. The construction disclosed in my prior patent heretofore identified will function satisfactorily when applied to hard wood, but does not function equally well in soft wood. Much of the use of characters of the kind here contemplated is for the display of street numbers, names, etc. as applied to buildings, the material of which is quite generally pine or other soft wood. A fastening device must therefore be provided that may easily be applied by the use of a hammer and that will remain permanently in place.

Furthermore, as the characters are individual, and as they are used in series, the attaching means must be so designed that the characters may be applied in exact alignment; in other words, the prongs must be so arranged that the act of driving the prongs into the wood will not tend to shift the position of the character.

The desired result is accomplished by providing pairs of sheet metal prongs arranged in parallel planes and in reversed relation relative to their high points. Thus, any tendency toward shifting of the character during driving, due to the triangular form

of a prong is offset by the opposite tendency of the adjacent prong.

The invention will be more readily understood by reference to the accompanying drawings, in which

Fig. 1 is a perspective view showing a series of characters constructed in accordance with my invention, the last of the series being in the process of being applied;

Fig. 2 is a back plan view of one of the characters;

Fig. 3 is an edge view thereof;

Fig. 4 is an end view;

Fig. 5 is an enlarged side elevation better showing the form of the reinforced prong; and

Fig. 6 is a plan view on the same scale as that of Fig. 5.

In the drawings, I have illustrated a support which may be a wood board 10. To this support has been secured a series of letters and characters 11. The last character, being the letter S, is in the process of being applied by the use of a common hammer.

The specific construction of the characters is preferably that of a length of sheet metal comprising a body portion 12 the ends 13 of which are doubled back on the body.

The fastening devices are of peculiar form and consist of pairs 14—15 of prongs of triangular form in outline and arranged in parallel planes. Each pair of prongs is formed by die action in striking the two prongs out of a substantially square area of metal. This results in the formation of triangular prongs that are oppositely disposed as to their high portions. However, prongs composed of relatively light gauge metal arranged in a plane are of doubtful strength and holding capacity in soft wood. I have therefore increased their holding capacity in soft wood, by providing flanges 16 along the edge at the high point. Preferably these flanges are not disconnected from the base at 17 in order to add to the resistance to bending of the prong as a whole. Preferably also, the flange is diminished in thickness at its upper end as at 18, merging into the point 19 of the prong.

Fastening prongs arranged and construct-

ed as described will be found to be of relatively great strength and of astonishing holding capacity in soft wood. The characters are economically constructed, the figures or letters being applied to the faces by enameling or similar means.

Obviously, the exact form and arrangement need not be followed in order to secure the benefits of this invention, and I do not wish to be limited except as indicated in the appended claims.

I claim:

- 15 1. The combination with a display character having a back, of a prong projecting from the back, said prong being of triangular outline in side elevation, and a flange projecting from and angularly disposed relative to the high end of the prong.
- 20 2. The combination with a display character having a support, of triangular sheet metal prongs at the back of and perpendicular to said support, the vertical edge of said prongs being flanged to stiffen the same and to increase their holding capacity in wood.
- 25 3. The combination with a display character having a support, of triangular sheet metal prongs at the back of and perpendicular to said support, the vertical edge of said prongs being flanged to stiffen the same and to increase their holding capacity in wood, the width of the flange diminishing toward the point of the prongs.
- 30 4. The combination with a character having a sheet metal back, of a triangular prong struck out of said metal, the body of said prong lying in a plane, the vertical edge of the prong being stiffened by a lateral flange, said flange diminishing in width toward the point of the prong.

40 In testimony whereof I have affixed my signature.

JAMES COOKE.
